UNITED STATES PATENT OFFICE.

FRANK W. OFELDT, OF PITTSBURGH, PENNSYLVANIA, ASSIGNOR OF ONE-HALF TO
FRANK McCARTHY, OF PITTSBURGH, PENNSYLVANIA.

VALVE MECHANISM FOR ENGINES.

1,359,523.

Specification of Letters Patent. Patented Nov. 23, 1920.

Application filed April 28, 1920. Serial No. 377,282.

To all whom it may concern:

Be it known that I, FRANK W. OFELDT, of Pittsburgh, Allegheny county, Pennsylvania, have invented a new and useful Improvement in Valve Mechanism for Engines, of which the following is a full, clear, and exact description, reference being had to the accompanying drawings, forming part of this specification, in which—

10 Figure 1 is a longitudinal section of an engine and valve mechanism embodying my invention;

Fig. 2 is a perspective view of the valve removed;

15 Fig. 3 is a detail sectional view illustrating the preferred form of ports;

Fig. 4 is a partial longitudinal section showing a modification; and

20 Fig. 5 is a perspective view of the valve shown in Fig. 4.

My invention has relation to valve mechanism for engines, and more particularly to valve mechanisms for distributing motive fluid to a multicylinder engine of the type in which the cylinders rotate about a fixed center. The term "engine," as used herein and in the appended claims, not only includes engines proper, but also pumps, compressors, etc., of the type just referred to.

30 An object of my invention is to provide valve mechanism of simple and efficient character whereby a single valve may be utilized to distribute motive fluid to a plurality of cylinders, the valve being so constructed and arranged that no special operating connections are required for it.

40 A further object of my invention is to provide a valve of this character in which there will be a minimum amount of wear between the valve and the valve seat, the movement of the valve relatively to the seat being such as to tend to maintain a perfect seating fit between the parts.

45 A still further object of the invention is to provide means of simple character whereby valves, such as above referred to, may be readily adjusted to vary the point of cut off and also the lead, as well as for reversing the engine.

50 The nature of my invention will be best understood by reference to the accompanying drawings in which I have illustrated two different embodiments thereof and

55 which will now be described, it being

premised, however, that various changes can be made in the details of construction, arrangement and combination of the various parts, without departing from the spirit and scope of my invention as defined 60 in the appended claims.

Referring first to that form of my invention shown in Figs. 1 and 2, the numeral 2 designates an outer stationary housing having at one end portion suitable supports 3 65 for a stationary crank shaft 4, having a crank pin 5. 6 designates two of the radially arranged cylinders of which any desired number may be employed, these cylinders being mounted in an inner casing or 70 housing member 7, which is arranged to rotate with the cylinders upon suitable bearings such as indicated at 8. 9 designates pistons which reciprocate in the cylinders and which are connected to the eccentric hub 10 by the connecting rods 11. Engines of this general type are well known in the art, and as my invention is not concerned with the details of the engine itself, they need not be further described. 80

The casing 7 is provided at one end with a concave valve seat 12, of approximately semi-spherical form, and from which leads the series of spaced ports 13, extending to the several cylinders. 85

14 designates the valve proper, which is of approximately semi-spherical form adapted to seat closely in the seat 12. The body of this valve is made hollow, as shown at 15, the hollow chamber so formed 90 communicating by a series of peripheral openings 16 with a continuous annular port 17, formed in the exterior of the valve body and extending entirely around the same, as best shown in Fig. 2. The valve is provided with a hollow stem 18, which extends within the coupling member 19, this coupling member being fitted within a co-operating coupling member 20, to which is attached a flexible supply pipe 21, for the 100 motive fluid. The valve is set obliquely with respect to the seat, so that its stem 18 is at an acute angle with respect to the crank 5. The end plate 22 of the rotatable casing 7 is provided with a central opening 23, through which the coupling member 19 with the valve stem therein projects into engagement with the coupling member 20. The coupling member 20 is slidably mounted on the curved guide bar 23, whereby the 110

angle of the bar, with respect to the crank pin may be varied, to thereby vary the point of cut off for each of the ports 13. The desired adjustment may be secured by any suitable means, such as the spring pawl 24, adapted to engage in one of a number of teeth 25 on the bar 23. Said end plate is also preferably rotatably seated in the casing, so that it may be rotated by means of a suitable handle 26. The effect of this rotation, as will be readily seen will be to vary the lead of the valve; or if said end plate be rotated to a sufficient extent, it will effect a reversal of the engine. Such reversal as well as changes in the lead of the valve may also be effected by rotating the crank shaft 4, by means of a suitable handle 27, provided with a locking pawl 28. As will be readily seen, the turning of the crank shaft will affect the angular position of the crank pin 5 with respect to the valve.

29 designates a pinion which is keyed or made fast to a sleeve 30, surrounding the crank shaft 4 and rigidly connected with the rotating casing 7. This pinion forms a means whereby power may be taken from the engine.

As will be readily understood, the reciprocation of the pistons in their respective cylinders will, through the connecting rods and eccentric hub, cause a rotation of said cylinders about the center of the crank shaft 4, thereby rotating the casing 7 and its valve seat 12. The valve will also be rotated about a different center than the engine, namely, about the center of its stem. So far as the distribution of motive fluid in the ports 13 is concerned, the effect will be precisely the same as if the valve 14 remained stationary, since the port 17 is a continuous annular port. By causing the valve to rotate about a different center, however, the engine can be run at a very high speed with comparatively little relative movement between the fitting surfaces of the valve and its seat. Furthermore, such relative movement as occurs between these surfaces is of a lapping or grinding nature which tends to constantly keep the parts to a proper seating fit.

In the modification shown in Figs. 4 and 5, the ports 13^a correspond to the ports 13 in Fig. 1 and lead to an arrangement of cylinders the same as shown in that figure. 57^a is a rotating casing corresponding to the casing 7, first described, and through which these ports extend. In this figure, however, these ports lead through a flat valve seat 12^a, and the valve 14^a instead of being of semi-spherical form, is of flat disk form with a hollow interior chamber 15 into which motive fluid is admitted through the hollow stem 18^a. The motive fluid escapes from the chamber 15^a through the peripheral openings 16^a, into the annular port 17^a,

which opens against the seat 12^a. The stem 18^a extends into the end plate 22^a of the casing, and which end plate may be rotated in the same manner as the plate 22, first described, to vary the lead or to reverse the motor.

In order to provide for a relatively quick opening and closing of the ports 13 or 13^a, these ports where they open through the valve seat 12 or 12^a are preferably of the triangular form, indicated in Fig. 3. The effect of this, in combination with the peculiar movement of the valve with respect to its seat, is to give a relatively quick opening and closing of the ports.

The advantages of my invention will be readily apparent, since it provides a single valve adapted to properly distribute the motive fluid to a plurality of rotating cylinders, and which is so constructed and arranged as to make it especially adapted for high speed engines. Owing to the simplicity of the construction and the absence of any special connecting parts for actuating the valve, an engine of any given horse power may be constructed in a very compact form. The arrangement whereby the relative movement which takes place between the valve and its seat is of a character to constantly grind the seating surfaces is also of importance.

I claim:

1. A multicylinder engine of the rotating cylinder type having a single valve seat provided with ports leading to the several cylinders and adapted to rotate with the cylinders, and a valve fitting said seat and mounted to rotate on a different center from the seat, substantially as described.

2. A multicylinder engine of the rotary cylinder type having a valve seat arranged to rotate with the cylinder and provided with ports leading to the respective cylinders, and a hollow rotary valve fitted to said seat and mounted to rotate about a center different from the center of rotation of the cylinders, said valve having a continuous annular port communicating with the hollow interior of the valve and co-operating with the ports in said seat, substantially as described.

3. A multicylinder engine of the rotary cylinder type having a valve seat arranged to rotate with the cylinder and provided with ports leading to the respective cylinders, and a hollow rotary valve fitted to said seat and mounted to rotate about a center different from the center of rotation of the cylinders, said valve having a continuous annular port communicating with the hollow interior of the valve and co-operating with the ports in said seat, said port being concentric with the axis of rotation of the valve, substantially as described.

4. A multicylinder engine of the rotary

cylinder type having a single valve seat provided with ports leading to the several cylinders and adapted to rotate with the cylinders, and a valve fitting said seat and

5 mounted to rotate on a different center from the seat, together with means for changing the position of the valve with respect to the center of the seat, substantially as described.

5. A multicylinder engine of the rotary 10 cylinder type having a single valve seat provided with ports leading to the several cylinders and adapted to rotate with the cylinders, and a valve fitting said seat and mounted to rotate on a different center from 15 the seat, together with means for adjusting the ports to vary the lead of the valve, substantially as described.

6. A rotary engine of the multicylinder 20 type in which the cylinders revolve about a fixed center, said engine having a valve seat arranged to rotate with the cylinders about said fixed center, and a single distributing valve fitted to said seat and arranged to be rotated with the cylinders and 25 about an axis which is different from the axis of rotation of the cylinders, substantially as described.

7. A rotary engine of the multicylinder 30 type in which the cylinders revolve about a fixed center, said engine having a valve seat arranged to rotate with the cylinders about said fixed center, and a single distributing valve fitted to said seat, and arranged to be rotated with the cylinders and about an axis 35 which is different from the axis of rotation of the cylinders, together with means for changing the position of the valve relatively to its seat, to thereby vary the point of cut off or the amount of lead, substantially as 40 described.

8. A multicylinder engine of the rotary cylinder type, in which the cylinders revolve about a fixed axis, said engine having a valve seat arranged to rotate with the cylinders 45 about such axis, and said seat having a plurality of ports leading to the respective cylinders, a hollow distributing

valve fitted to said seat and having an annular exterior port coöperating with the ports in said seat and communicating with the hollow interior of the valve, said valve having a hollow stem provided with a supply connection for motive fluid and the valve and stem being held to rotate under the rotary action of the seat about a center 55 which is different from the center of rotation of the cylinders, substantially as described.

9. A multicylinder engine of the rotary cylinder type in which the cylinders revolve 60 about a fixed axis, said engine having a valve seat arranged to rotate with the cylinders about such axis, and said seat having a plurality of ports leading to the respective cylinders, a hollow distributing valve fitted 65 to said seat and having an annular exterior port coöperating with the ports in said seat and communicating with the hollow interior of the valve, said valve having a hollow stem provided with a supply connection for 70 motive fluid and the valve and stem being held to rotate under the rotary action of the seat about a center which is different from the center of rotation of the cylinders, together with means for changing the position 75 of the valve relatively to its seat to thereby vary the point of cut off or the lead of the valve, substantially as described.

10. A rotary engine of the multicylinder 80 type in which the cylinders rotate about a fixed axis and having a single distributing valve arranged to rotate about a different axis, substantially as described.

11. A rotary engine of the multicylinder 85 type in which the cylinders rotate about a fixed axis having a single distributing valve arranged to rotate about a different axis, said valve being mounted for rotation by the engine about an axis which is different from the axis about which said cylinders rotate, substantially as described.

In testimony whereof, I have hereunto set my hand.

FRANK W. OFELDT.
